MUFFLE FURNACE

Thomas Edward Bridgford, Dudley, England, assignor to Gibbons Brothers Limited, Dudley, England, a company of Great Britain

Application September 23, 1933, Serial No. 690,741
In Great Britain September 27, 1932

12 Claims. (Cl. 263—42)

This invention relates to muffle furnaces of the oven type wherein the oven is provided with one or more longitudinally arranged combustion chambers having one or more hollow walls 5 through which the atmosphere of the oven can circulate.

The object of the present invention is to provide an improved construction of combustion chamber for use in such furnaces.

10 Referring to the drawing:

Figure 1 is a view in sectional end elevation showing the general arrangement of a muffle furnace oven containing two of the improved combustion chambers.

15 Figure 2 is a sectional view taken through one of the chambers.

Figure 3 is a side view of the chamber.

Figure 4 is a sectional view on line 4—4 of Figure 2.

20 In the construction illustrated, the invention is shown as applied to a muffle furnace having two combustion chambers 1 arranged one at either side of the oven or muffle chamber.

Each combustion chamber is of triangular 25 shape in cross section as shown in Figure 2, and its inclined sides are hollow or formed with cavities.

The inner wall 2 of each of these sides is 30 formed of members extending from top to bottom, but may be formed in a plurality of pieces, and these members 2 may be made of a highly refractory material such as silicon carbide.

The members 2 are provided with integral ribs 3 arranged in spaced relationship upon their outer 35 sides.

The members 2 are provided with projecting 40 hollow ribs 4 at opposite edges which interengage with similar ribs upon the adjacent members as shown clearly in Figure 4, and the arrangement 45 may be such that air can circulate through the openings 5 in the projections 4.

The outer wall of each of the hollow sides is 50 built up of a number of channel section bricks 6, these bricks extending in between the ribs 3 45 and having projecting shoulders 7 which engage each other.

55 Separately constructed inserts or closure members 8 are provided, these members being shoudered as shown at 9 and being employed for closing the open sides of the channel 6.

These members 8 may be provided in various thicknesses so that the heat conductivity of the inner wall of the combustion chamber as a whole can be varied as desired.

55 The members 6 at the tops and bottoms of the

hollow walls are provided with openings 10 so that air from the oven can enter the hollow walls freely.

Near the top the inner members 2 are provided with integral ribs or projections 11 which support sealing tiles 12, and further sealing tiles 13 of double dovetail section may be employed so as to constitute a second seal.

The base 14 of the improved combustion chamber is formed as a single member, but may be 10 built up from a plurality of members, and it is provided with openings 15 to allow of air circulation.

Further, the base 14 is supported upon spaced 15 bricks 16, the spaces between the bricks corresponding with the openings 15 and the openings through the bricks 6 so that air can circulate freely through the hollow walls and also under the base.

The bricks 6 and the closure members 8 are 20 made of a refractory material such as fire clay.

The floor of the furnace is provided with spaced hollow ribs 17, and the products of combustion after passing through the combustion chambers 1 are directed to these hollow ribs by 25 flues 18, so that the said combustion products can be used to heat up the floor of the furnace.

These hollow ribs 17 are not however essential 30 and the improved combustion chamber is applicable generally to muffle ovens, the products of combustion passing, for example, from the end 35 of the combustion chambers to the chimney or exhaust flue.

What I claim then is:—

1. A muffle furnace of the oven type having a 35 combustion chamber at the side of the oven and extending longitudinally thereof, spaced inner and outer walls forming a hollow side to said combustion chamber, the atmosphere of the oven being adapted to circulate through said hollow 40 side, the outer wall of said hollow side, in contact with the oxidizing atmosphere of the oven, being formed from non-oxidizing refractory material, and the inner wall of said hollow side, in contact with the combustion gases, being formed from a 45 highly refractory material and inserts of non-oxidizing refractory material at the outer surface of said inner wall to shield said surface from the oxidizing atmosphere of the oven.

2. A muffle furnace of the oven type having a 50 combustion chamber along each longitudinal side of the oven, each side of each combustion chamber being hollow to allow circulation therethrough of the atmosphere of the oven, spaced inner and outer walls forming each of said sides, the outer 55

- the inner surface of each inner wall to support said sealing tiles, spaced ribs projecting from the outer surface of said wall, an outer wall spaced from said inner wall by said ribs, said outer wall being built up from channel section bricks engaging between the spaced ribs on said inner wall, and a closure member for the inner side of each of said channel section bricks, said closure member being interposed between said brick and the outer surface of said inner wall.
11. A muffle furnace of the oven type having a combustion chamber at the side of the oven and extending longitudinally thereof, a base for said combustion chamber, two sides extending upwardly from said base in converging relationship, sealing tiles filling the joint at the upper ends of said sides, each side of each combustion chamber being hollow to allow circulation therethrough of the atmosphere of the oven, an inner wall for each side, said inner wall being built up from slabs, interengaging hollow ribs at the meeting edges of adjacent slabs, spaced ribs projecting from the outer surface of said wall, an outer wall, said outer wall being built up from channel section bricks engaging between the spaced ribs on said inner wall, and a closure member for the inner side of each of said channel section bricks,
12. A muffle furnace of the oven type having a combustion chamber along each longitudinal side of the oven, a base for each combustion chamber, spaced bricks between said base and the floor of the oven to allow the oven atmosphere to circulate beneath said base, two sides extending upwardly from said base in converging relationship, sealing tiles filling the joint at the upper ends of said sides, each side of each combustion chamber being hollow to allow circulation therethrough of the atmosphere of the oven, an inner wall for each side, said inner wall being built up from slabs, interengaging hollow ribs at the meeting edges of adjacent slabs, spaced ribs projecting from the outer surface of said wall, an outer wall, said outer wall being built up from channel section bricks engaging between the spaced ribs on said inner wall, and a closure member for the inner side of each of said channel section bricks, said closure member being interposed between said brick and the outer surface of said inner wall.

THOMAS EDWARD BRIDGFORD.
